MINING MACHINE

Charles F. Osgood, Claremont, N. H., assignor to
Sullivan Machinery Company, a Corporation of
Massachusetts

Application October 20, 1930. Serial No. 489,890

21 Claims. (Cl. 262—30.)

This invention relates to mining machines and more particularly has reference to improvements in the flexible feeding means of a coal mining machine of the continuous cutter, bottom cutting type.

An object of this invention is to provide an improved coal mining machine. A further object is to provide an improved coal mining machine having improved feeding means. Another object is to provide an improved mining machine of the flexibly fed, continuous cutter, bottom cutting type which is extremely low in height and especially adapted to use in lowvein work. A further object of this invention is to provide an improved mining machine of the flexibly fed, room and pillar type. Another object is to provide an improved mining machine of the aforesaid character having improved feeding and guiding means whereby the machine may be fed and controlled in a more facile and expeditious manner. A further object is to provide an improved mining machine of the room and pillar lowvein type having improved feeding and guiding mechanism wherein separate relatively rotatable, power operated and controlled feeding and controlling members respectively cooperating with separate flexible feeding elements are employed for feeding and guiding the machine for sliding movement over the mine floor, the feeding and controlling members and the driving mechanisms therefore being arranged in an improved manner on the machine whereby the latter is rendered extremely compact vertically. These and other objects and advantages of this invention will, however, hereinafter more fully appear.

In the accompanying drawings there is shown for purposes of illustration two forms which the invention may assume in practice.

In these drawings,—

Fig. 1 is a plan view of the illustrative embodiment of a mining machine constructed in accordance with the preferred form of the invention;

Fig. 2 is a side elevational view of the machine shown in Fig. 1;

Fig. 3 is an enlarged plan view of the forward portion of the improved mining machine, parts being shown in horizontal section to illustrate structural details;

Fig. 4 is a central, longitudinal extending, vertical sectional view taken substantially on line 4—4 of Figs. 1 and 3;

Fig. 5 is a transverse vertical sectional view taken on line 5—5 of Figs. 1 and 3;

Fig. 6 is a detail sectional view illustrating the central bearing support for one of the haulage drums;

Fig. 7 is a view similar to Fig. 1 illustrating a modified form of construction;

Fig. 8 is a side elevational view of the machine shown in Fig. 7;

Fig. 9 is an enlarged horizontal sectional view illustrating a portion of the driving gearing for the cutting and feeding mechanisms;

Fig. 10 is a central, longitudinally extending, vertical sectional view taken substantially on line 10—10 of Figs. 7 and 9; and

Fig. 11 is a transverse vertical sectional view taken substantially on line 11—11 of Figs. 7 and 9.

In the illustrative form of the invention shown in Figs. 1 to 6 inclusive there is shown a coal mining machine of the flexibly fed, continuous cutter, room and pillar type generally comprising a machine frame or body 1 of generally rectangular shape having a plane bottom surface 2 on which the machine is supported for sliding movement over the mine floor. The frame or body comprises a rear motor section 3 and a front cutter carrying and feed section 4. As is usual in the mining machines of the room and pillar type, rigidly secured within the front frame section 4 and projecting forwardly lengthwise of the machine is an elongated plane cutter bar 5 supporting on its margin an endless cutter bit carrying cutter chain 6. In the present construction the motor frame section 3 rests directly on its bottom on the mine floor and the vertical dimension of this motor substantially determines the height of the machine. This motor may be of the reversible type having its power shaft 7 horizontally disposed midway between the top and bottom of the motor frame and extending longitudinally of the machine. Arranged at the forward end of the machine at opposite sides of the longitudinal median line thereof are relatively rotatable feed operating and controlling members 8 and 9 herein in the form of cable winding or haulage drums with which flexible feeding and controlling elements 10 and 11, herein cables or ropes, respectively cooperate.

The haulage drums 8 and 9 are disposed on parallel vertical axes in a novel manner and these drums and the cutter chain 6 are operatively connected to the forward end of the motor shaft through improved transmission means to be hereinafter described. If desired the feeding and controlling cables may be extended directly from the haulage drums during the feeding of the machine but in the present instance, there are provided suitable guide sheaves and the cables, after passing around any preferred guide sheaves, may be extended in any preferred direction from the machine and attached to suitably positioned anchors in the manner which is well understood in the mining machine art.

Now referring to the improved feeding and cutting mechanisms and more particularly to the improved transmission means therefor, it will be noted that secured to the forward end of the motor shaft 7 is a spur pinion 15 meshing with an internal gear 16 fixed to a horizontal longi-

100

105

110

115

120

tudinally extending transmission shaft 17. This shaft is suitably journaled within the front frame section 4 and is arranged with its axis lying in the central longitudinally extending vertical plane of the machine. Secured to and rotatable with the internal gear 16 is a bevel pinion 18 meshing with a large bevel gear 19 rotatable in a horizontal plane beneath the longitudinal shaft 17, as clearly shown in Fig. 4. The hub of this bevel gear is suitably journaled within the frame section 4 and is connectible by a sliding clutch 20 of a usual design to a vertical shaft 21. The sliding clutch 20 is provided with usual shipper mechanism 22 having an operating handle 23. The shaft 21 is suitably journaled within the frame section 4 and has fixed thereto a sprocket 24 which engages and drives, in the manner well understood in the art, the cutter chain 6. This cutter chain sprocket is arranged within a chamber 25 extending transversely beneath and through the sides of the frame, as shown in Fig. 2, and this chamber forms a cuttings passage through which the cuttings brought back by the cutter chain are expelled. It will thus be seen that the cutter chain may be connected in driving relation with the motor or remain idle at will. Fixed to the forward end of the shaft 17 is a spur gear 26 meshing with a spur gear 27 keyed to a horizontal shaft 28 herein arranged parallel with, and above the shaft 17 and likewise suitably journaled within the frame section 4. In the present instance, the spur gears 26, 27 are change speed gears and may be removed and replaced with gears having different tooth ratio so that differently related predetermined feeding speeds may be obtained. Herein keyed to the shafts 17 and 28 are worms 29 and 30, the worm 29 having teeth of steeper lead and oppositely inclined from the teeth of the worm 30. However, since the shafts 17 and 28 rotate in opposite directions the worms effect drive in the same direction although at different speeds. Separate and distinct plural predetermined speed transmission mechanisms generally designated 31 and 32 are provided between the worms 29, 30 and the haulage drums 8 and 9 respectively, and as the structure of each of these transmission mechanisms is substantially identical, the description of one will suffice for both.

Now referring to the plural predetermined speed transmission mechanism 31 between the worms and the haulage drum 8, it will be observed that meshing with the worm 29 is a fast speed worm wheel 33, while meshing with the worm 30 is a slow speed worm wheel 34, these worm wheels being arranged on aligned vertically extending axes parallel with the axis of the haulage drum. These worm wheels are suitably journaled within the frame section 4 and are arranged in an extremely compact manner thereby reducing the vertical dimension of the feeding mechanism to a minimum. Journaled within bearings supported by the hubs of these worm wheels is a vertical shaft 35 and the worm wheels are selectively connectible to this shaft by means of multiple disc clutches 36 and 37 respectively, of a usual design. Keyed to the lower end of the vertical shaft 35 is a spur pinion 38 meshing with the teeth of an internal gear 39 herein formed integral with the haulage drum 8. It will thus be seen that when friction clutch 36 is applied and clutch 37 released, the haulage drum 8 may be driven in winding direction at a relatively high speed through gearing 15, 16, shaft 17, worm gearing 29, 33, shaft 35 and the spur pinion 38

meshing with the internal gear 39 secured to the drum. It will also be seen that when clutch 36 is released and clutch 37 applied the haulage drum 8 may be driven in winding direction at a relatively slow speed appropriate for cutting through the reduction gearing 26, 27 and worm gearing 30, 34. As previously mentioned, the transmission mechanism 32 for the haulage drum 9 is substantially identical to that for the haulage drum 8 and includes fast and slow speed worm wheels 40 and 41 meshing with the worms 29 and 30 respectively and connectible by similar multiple disc clutches 42 and 43 in driving relation with the haulage drum 9. When one or the other of the friction clutches 42, 43 is applied and the other released, the hauling drum 9 may be rotated in winding direction at either a relatively high speed or a relatively low cutting speed, depending upon which one of the clutches is applied. It will be noted that the haulage drums may be rotated separately or simultaneously and that the friction clutches may be so released as to permit the drums to rotate in unwinding direction under various degrees of frictional resistance. Upon full release of the clutches the drums may rotate freely. If desired a usual main haulage drum controlling clutch may be interposed in the drive between the vertical shaft 35 and the drum or in any other suitable location so that at certain times the drums may be entirely disconnected from their drive, for instance, when it is desired to unwind the feed cables from the drums by hand. Such clutches are usual in mining machines of the type disclosed and as they do not per se enter into this invention, illustration of the same is thought to be unnecessary.

The operating means for the friction clutches 36, 37 within the worm wheels 33, 34 respectively herein comprises a shipper yoke 44 pivoted at 45 on the machine frame and equipped with rollers 46 engageable with the opposite plane surfaces of cylindrical pressure plates 47 and 48 for the clutches respectively. The means for swinging the shipper yoke about its pivot comprises a shaft 49 rotatably mounted within suitable bearings carried within the frame section 4 and having an eccentric portion 50 pivotally connected to the shipper yoke. Secured to the outer end of the shaft 49 at the rear end of the machine is an operating handle 51. It will thus be seen that when the handle 51 is rotated in one direction or the other the shipper yoke 44 is swung upwardly or downwardly about its pivot to apply either the clutch 36 or the clutch 37. The parts are so arranged that it is impossible to effect simultaneously application of the clutches, one clutch always being released when the other is applied and when the shipper yoke is in its neutral position both clutches are released. Similar operating mechanism including a shipper yoke 52, operating shaft 53 and operating handle 54 is employed for controlling the friction clutches 42, 43 in the drive for the haulage drum 9. Each of the haulage drums 8 and 9 is journaled within the frame section 4 in a similar manner, and, as shown in Fig. 6, the haulage drum 8 is provided with a hub portion 55 rotatably supported on ball bearings 56 within the machine frame. A spacing sleeve 57 and a central holding bolt 58 are provided for maintaining the drum bearings in proper spaced relation. As shown in Fig. 5, the haulage drums 8 and 9 are arranged within a chamber 59 extending transversely completely across the frame section 4 above the rear end of the cutter bar 5 so

that the feed cables may be extended from the drums in various directions.

In the form of the invention shown in Figs. 7 to 11 inclusive, there is disclosed a mining machine of the same general character as that described above except in this form of construction the feeding and controlling drums are arranged at the rear end of the machine and the feeding and cutting mechanisms are driven from the rear end of the motor, the motor being located at the front end of the machine above the cutter bar. This machine comprises a frame or body 65 of generally rectangular shape having a plane bottom surface 66 on which the machine is slidably supported for movement over the mine floor. The frame or body comprises a bed section 67, a motor section 68 and a rear cutter and feed section 69. Rigidly secured within the bed section 67 and projecting forwardly lengthwise of the machine, is an elongated plane cutter bar 70 carrying a usual endless cutter bit carrying cutter chain 71. Arranged at the rear end of the machine at opposite sides of the longitudinal median line thereof are relatively rotatable feed operating and controlling members 72 and 73 herein in the form of cable winding or haulage drums with which flexible feeding and controlling elements 74 and 75 herein cables or ropes respectively cooperate. As mentioned above the motor 68 is arranged at the front end of the machine above the cutter bar 70 and herein may be of the reversible type having its power shaft 76 horizontally disposed and extending longitudinally of the machine. The haulage drums 72, 73 are disposed on parallel vertical axes in a novel manner and the cutter chain and the haulage drums are connected to the rear end of the motor shaft through improved transmission means. As in the form of the invention described above, suitable guide sheaves are provided around which the feeding and controlling cables may pass in the feeding and guiding of the machine, as is usual in machines of the character disclosed.

The improved transmission means between the motor and the feeding and cutting mechanisms herein comprises a spur pinion 77 meshing with an intermediate gear 78 in turn meshing with an internal gear 79. This internal gear is suitably journaled within the frame section 69 and is fixed to a horizontal longitudinally extending shaft 80 suitably journaled within the frame section 69. Fixed to the hub of the internal gear 79 is a bevel pinion 81 meshing with a large bevel gear 82 rotating in a horizontal plane beneath the shaft 80 as clearly shown in Fig. 10. This bevel gear is suitable journaled within the frame section 69 and is connectible by a sliding clutch 83 of a usual design to a vertical shaft 84. This sliding clutch is provided with a usual shipper mechanism 85 having a control handle 86. Shaft 84 is suitably journaled within the frame sections 67 and 69 and has keyed thereto at its lower end a spur pinion 87 meshing with a spur gear 88 keyed to a vertical shaft 89 likewise suitably journaled within the frame sections 67, 69. Fixed to the hub of this spur gear is a sprocket 90 which engages and drives the cutter chain 71 in the usual manner. In this form of the invention the cutter chain extends beneath the frame sections 68, 69 and the drive sprocket 90 is located at the rear end of the machine beneath the haulage drums so that the cuttings brought back by the cutter chain are discharged rearwardly through a passage 91 opening through the rear end of the machine frame. Fixed to the

rear end of the shaft 80 is a spur gear 92 meshing with a spur gear 93 fixed to a horizontal shaft 94 arranged parallel with and above the shaft 80 and likewise suitably journaled within the frame section 69. Herein keyed to the shafts 80 and 94 are worms 95 and 96 respectively, similar to the worms 29 and 30 in the form of the invention described above. These worms 95 and 96 are connected to the haulage drums respectively through separate and distinct plural predetermined speed transmission mechanisms generally designated 97 and 98 and which in the present instance are identical to the plural speed transmission mechanisms 31 and 32 described above, and each comprises coaxial fast and slow speed worm wheels 99 and 100 controlled by multiple disc clutches 101 and 102 respectively. Therefore since these mechanisms are the same as those previously described, a repetition of the description of the same is thought unnecessary other than to state that the haulage drums 72, 73 may be rotated either separately or simultaneously in a direction to wind in their respective cables at relatively high speed or at relatively low speed and that these haulage drums 100 may rotate in unwinding direction under various degrees of frictional resistance or without such resistance. Various modes of operation of both forms of the improved mining machine will be clearly apparent to those skilled in the art and as the method of use of a room and pillar mining machine is well known, further description of the operation of the machine is thought unnecessary.

As a result of this invention it will be observed that an extremely low, comparatively short, compact machine is produced and one which is accordingly well adapted to use in the lowest commercially workable veins of coal. Furthermore this improved construction enables an extremely compact machine to be obtained wherein the length thereof is reduced to a minimum, the improved feed mechanism and the novel compact arrangement of the driving gears and haulage drums on the mining machine reducing the dimensions of the machine to a minimum. Furthermore by arranging the haulage drums in the novel manner disclosed and by providing the improved arrangement of the transmission mechanism for driving the haulage drums and the cutting mechanism, the machine is not only rendered extremely compact, but is also exceedingly flexible in operation and easy to handle especially during the various maneuvering of the machine to position the same to effect its sumping, transverse and withdrawal cuts in accordance with the room and pillar method of mining. It will still further be noted that the improved feeding mechanism and cutting mechanism are extremely well balanced and symmetrical in design, the driving mechanism for the haulage drums being substantially identical in construction, thereby reducing the number of different parts with the resultant decrease in the cost of manufacture and replacement. These and other uses and advantages of the improved mining machine will be clearly apparent to those skilled in the art.

While there is in this application specifically described two forms which this invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a mining machine, a machine frame adapted to rest upon and slide in any direction over the mine floor, a horizontal motor carried by said frame having its power shaft extending longitudinally of the machine, cutting mechanism driven from one end of said motor including a kerf cutter projecting forwardly from said frame, and feeding mechanism driven from the same end of said motor including relatively rotatable feed operating and controlling members disposed with their axes parallel to a transverse vertical plane and disposed wholly above the uppermost plane of said kerf-cutter, said members each adapted to cooperate directly with flexible feeding means, and mechanism for effecting rotation of said members either separately or simultaneously at relatively high speed or at relatively low speed whereby one member may be driven at a relatively low speed while the other member is simultaneously driven at a high speed.

2. In a mining machine, a machine frame
adapted to rest upon and slide in any direction
over the mine floor, a horizontal motor carried
by said frame having its power shaft extending
longitudinally of the machine, cutting mecha-
nism driven from one end of said motor including
a kerf cutter projecting forwardly from said
frame, and feeding mechanism driven from the
same end of said motor including relatively ro-
tatable feed operating and controlling members
disposed with their axes parallel to a transverse
vertical plane and disposed wholly above the
uppermost plane of said kerf-cutter, said mem-
bers each adapted to cooperate directly with
flexible feeding means, and mechanism for effect-
ing rotation of said members either separately or
simultaneously in a direction to draw in their
respective flexible feeding means at relatively
high speed or at relatively low speed whereby
one member may be driven at a relatively low
speed while the other member is simultaneously
driven at a high speed.

45 3. In a mining machine, a machine frame
adapted to rest upon and slide in any direction
over the mine floor, a horizontal motor carried
by said frame having its power shaft extending
longitudinally of the machine, cutting mecha-
50 nism driven from one end of said motor includ-
ing a kerf cutter projecting forwardly from said
frame, and feeding mechanism driven from the
same end of said motor including relatively ro-
tatable feed operating and controlling members
55 disposed on vertical axes in adjacency with the
rearward end of the kerf cutter and in planes
above the plane of said kerf cutter, said members
each adapted to cooperate directly with flexible
feeding means, and mechanism for effecting ro-
60 tation of said members either separately or si-
multaneously in a direction to draw in their re-
spective flexible feeding means at relatively high
speed or at relatively low speed whereby one
65 member may be driven at a relatively low speed
at a high speed.

4. In a mining machine, a machine frame adapted to rest upon and slide in any direction over the mine floor, a horizontal motor carried by said frame having its power shaft extending longitudinally of the machine, cutting mechanism driven from one end of said motor including a kerf cutter projecting forwardly from said frame, and feeding mechanism driven from the same end of said motor including relatively

rotatable feed operating and controlling members disposed on parallel vertical axes in adjacency with the rearward end of the kerf cutter and in planes above the plane of said kerf cutter, said members each adapted to cooperate directly with flexible feeding means, and mechanism for effecting rotation of said members either separately or simultaneously in a direction to draw in their respective flexible feeding means at relatively high speed or at relatively low speed whereby one member may be driven at a relatively low speed while the other member is simultaneously driven at a high speed. 80 85

5. In a mining machine, a machine frame adapted to rest upon and slide in any direction over the mine floor, a motor carried by said frame having its power shaft extending longitudinally of the machine, cutting mechanism driven from the forward end of said motor including a kerf cutter projecting forwardly from said frame, and feeding mechanism driven from the front end of said motor including relatively rotatable feed operating and controlling members disposed at the forward end of the machine on axes parallel to a transverse vertical plane and overlying the rearward portion of said kerf cutter, said members each adapted to cooperate directly with flexible feeding means and mechanism for rotating said members either separately or simultaneously in a direction to draw in their respective flexible feeding means at relatively high speed or at relatively low speed whereby one member may be driven at a relatively low speed while the other member is simultaneously driven at a high speed. 90 95 100 105 110

6. In a mining machine, a machine frame adapted to rest upon and slide in any direction over the mine floor, a motor carried by said frame and having its power shaft extending longitudinally of the machine, kerf cutting mechanism 115 driven from the rear end of said motor including a kerf cutter projecting forwardly from said frame, and feeding mechanism driven from the rear end of said motor including relatively rotatable feed operating and controlling members 120 disposed at the rear end of the machine on vertical axes and in planes above the plane of said kerf cutter, said members each adapted to co-operate directly with flexible feeding means, and mechanism for rotating said members either separately or simultaneously in a direction to draw in their respective flexible feeding means at 125 relatively high speed or at relatively low speed.

7. In a mining machine, a machine frame adapted to rest upon and slide in any direction over the mine bottom, kerf cutting mechanism carried by said frame including a horizontally projecting kerf cutter, and feeding mechanism including relatively rotatable feed operating and controlling members disposed on vertical axes and rotating in planes above the plane of said kerf cutter and each adapted to cooperate directly with flexibly feeding means, and motor operated driving mechanism for said members whereby one member may be driven at a relatively low speed while the other member is simultaneously driven at a relatively high speed. 130 135 140

8. In a mining machine, a machine frame adapted to rest upon and slide in any direction over the mine bottom, kerf cutting mechanism carried by said frame including a horizontally projecting kerf cutter, and feeding mechanism including relatively rotatable feed operating and controlling members disposed on vertical axes and rotating in planes above the plane of said 145
150

- kerf cutter and each adapted to cooperate directly with flexible feeding means, and mechanism for rotating said members either separately or simultaneously to draw in their respective flexible feeding means, and motor operated driving mechanism for said members whereby one member may be driven at a relatively low speed while the other member is simultaneously driven at a relatively high speed.

9. In a mining machine, a machine frame adapted to rest upon and slide in any direction over the mine bottom, kerf cutting mechanism carried by said frame including a horizontally projecting kerf cutter, and feeding mechanism including relatively rotatable feed operating and controlling members disposed on vertical axes and rotating in planes above the plane of said kerf cutter and each adapted to cooperate directly with flexible feeding means, and mechanism for rotating said members either separately or simultaneously to draw in their respective flexible feeding means at relatively high speed or at relatively low speed, and motor operated mechanism for said members whereby one member may be driven at a relatively low speed while the other member is simultaneously driven at a relatively high speed.

10. In a mining machine, a machine frame adapted to rest upon and slide in any direction over the mine floor, a motor disposed at the rear end of said frame and having a power shaft extending longitudinally of the machine, kerf cutting mechanism driven from the forward end of said motor including a kerf cutter projecting forwardly from said frame, and feeding mechanism driven from the forward end of said motor including relatively rotatable feed operating and controlling members disposed on axes parallel to a transverse vertical plane and at the forward end of the machine and overlying the rearward portion of said kerf cutter, said members each adapted to cooperate directly with flexible feeding means, and a separate and distinct plural speed transmission mechanism for each member whereby said members may be independently rotated at a plurality of predetermined speeds.

11. In a mining machine, a machine frame adapted to rest upon and slide in any direction over the mine floor, a motor disposed at the rear end of said frame and having a power shaft extending longitudinally of the machine, kerf cutting mechanism driven from the forward end of said motor including a kerf cutter projecting forwardly from said frame, and feeding mechanism driven from the forward end of said motor including relatively rotatable feed operating and controlling members disposed on vertical axes at the forward end of the machine and in planes above the plane of said kerf cutter, said members each adapted to cooperate directly with flexible feeding means, and a separate and distinct plural speed transmission mechanism for each member whereby said members may be independently rotated at a plurality of predetermined speeds.

12. In a mining machine, a frame carrying a rearwardly located horizontal motor and slidable in any direction over the mine floor, said motor having its power shaft extending longitudinally of the machine, cutting mechanism driven from the forward end of said motor power shaft including a forwardly projecting kerf cutter, and feeding mechanism driven from the forward end of said motor power shaft including relatively rotatable feed operating and controlling members arranged at the forward end of the machine on axes parallel to a transverse vertical plane and

overlying the rearward portion of said kerf cutter, said members each adapted to cooperate directly with flexible feeding means, and mechanism for effecting rotation of said members either separately or simultaneously at relatively low speed or at relatively high speed including for each member fast and slow predetermined speed transmission mechanism through which it, but not the other member, is driven.

13. In a mining machine, a frame carrying a rearwardly located horizontal motor and slidable in any direction over the mine floor, said motor having its power shaft extending longitudinally of the machine, cutting mechanism driven from the forward end of said motor power shaft including a forwardly projecting kerf cutter, and feeding mechanism driven from the forward end of said motor power shaft including relatively rotatable feed operating and controlling members arranged at the forward end of the machine on axes parallel to a transverse vertical plane and overlying the rearwards portion of said kerf cutter, said members each adapted to cooperate directly with flexible feeding means, and mechanism for effecting rotation of said members either separately or simultaneously in a direction to draw in their respective flexible feeding means at relatively low speed or at relatively high speed including for each member fast and slow predetermined speed transmission mechanism through which it, but not the other member, is driven.

14. In a mining machine, a frame carrying a rearwardly located horizontal motor and slidable in any direction over the mine floor, said motor having its power shaft extending longitudinally of the machine, cutting mechanism driven from the forward end of said motor power shaft including a forwardly projecting kerf cutter, and feeding mechanism driven from the forward end of said motor power shaft including relatively rotatable feed operating and controlling members arranged at the forward end of the machine on axes parallel to a transverse vertical plane and overlying the rearward portion of said kerf cutter, said members each adapted to cooperate directly with flexible feeding means, and mechanism for effecting rotation of said members either separately or simultaneously in a direction to draw in their respective flexible feeding means at relatively low speed or at relatively high speed including for each member fast and slow predetermined speed transmission mechanism through which it, but not the other member, is driven, and control mechanism included in each transmission mechanism to permit each member to rotate in a direction to pay out its flexible feeding means under various degrees of frictional resistance.

15. In a mining machine, a frame carrying a rearwardly located horizontal motor and slidable in any direction over the mine floor, said motor having its power shaft extending longitudinally of the machine, cutting mechanism driven from the forward end of said motor power shaft including a forwardly projecting kerf cutter, and feeding mechanism driven from the forward end of said motor power shaft including relatively rotatable feed operating and controlling members arranged at the forward end of the machine on axes parallel to a transverse vertical plane and overlying the rearward portion of said kerf cutter, said members each adapted to cooperate directly with flexible feeding means, and mechanism for effecting rotation of said members either

- separately or simultaneously in a direction to draw in their respective flexible feeding means at relatively low speed or at relatively high speed including for each member fast and slow predetermined speed transmission mechanism through which it, but not the other member, is driven, and control mechanism included in each transmission mechanism to permit each member to rotate in a direction to pay out its flexible feeding means under various degrees of frictional resistance or without such resistance.
16. In a mining machine, a frame carrying a rearwardly located horizontal motor and slidable in any direction over the mine floor, said motor having its power shaft extending longitudinally of the machine, cutting mechanism driven from the forward end of said motor power shaft including a forwardly projecting kerf cutter, and feeding mechanism driven from the forward end of said motor power shaft including relatively rotatable feed operating and controlling members disposed in planes above the plane of said kerf cutter on vertical axes at the forward end of the machine and each adapted to cooperate directly with flexible feeding means, and mechanism for effecting rotation of said members either separately or simultaneously at relatively low speed or at relatively high speed including for each member fast and slow predetermined speed transmission mechanism through which it, but not the other member, is driven.
17. In a mining machine, a frame carrying a rearwardly located horizontal motor and slidable in any direction over the mine floor, said motor having its power shaft extending longitudinally of the machine, cutting mechanism driven from the forward end of said motor power shaft including a forwardly projecting kerf cutter, and feeding mechanism driven from the forward end of said motor power shaft including relatively rotatable feed operating and controlling members arranged on parallel vertical axes in advance of said motor and in planes above the plane of said kerf cutter, said members each adapted to cooperate directly with flexible feeding means, and mechanism for effecting rotation of said members either separately or simultaneously at relatively low speed or at relatively high speed including for each member fast and slow predetermined speed transmission mechanism through which it, but not the other member, is driven.
18. In a mining machine, a rearwardly located horizontal motor having its casing resting directly upon and slidable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting kerf cutter, and feeding mechanism driven from the forward end of said motor power shaft including relatively rotatable feed operating and controlling members arranged at the forward end of the machine on parallel axes in planes above the plane of said kerf cutter and each adapted to cooperate directly with flexible feeding means, and mechanism for effecting rotation of said members either separately or simultaneously at relatively low speed or at relatively high speed including for each member fast and slow predetermined speed transmission mechanism through which it, but not the other member, is driven.
19. In a mining machine, a rearwardly located horizontal motor having its casing resting directly upon and slidable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting kerf cutter, and feeding mechanism driven from the forward end of said motor power shaft including relatively rotatable feed operating and controlling members disposed in planes above the plane of said kerf cutter on vertical axes at the forward end of the machine and each adapted to cooperate directly with flexible feeding means, and mechanism for effecting rotation of said members either separately or simultaneously at relatively low speed or at relatively high speed including for each member fast and slow predetermined speed transmission mechanism through which it, but not the other member, is driven.
20. In a mining machine, a rearwardly located horizontal motor having its casing resting directly upon and slidable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting kerf cutter, and feeding mechanism driven from the forward end of said motor power shaft including relatively rotatable feed operating and controlling members arranged in planes above the plane of said kerf cutter on parallel axes at the forward end of the machine, one at the advancing side of the machine and the other at the receding side thereof, and each adapted to cooperate directly with flexible feeding means, and mechanism for effecting rotation of said members either separately or simultaneously at relatively low speed or at relatively high speed including for each member fast and slow predetermined speed transmission mechanism through which it, but not the other member, is driven.
21. In a mining machine, a frame carrying a rearwardly located horizontal motor and slidable in any direction over the mine floor, said motor having its power shaft extending longitudinally of the machine, cutting mechanism driven from the forward end of said motor power shaft including a forwardly projecting kerf cutter, and feeding mechanism driven from the forward end of said motor power shaft including relatively rotatable feed operating and controlling members arranged at the forward end of the machine on axes parallel to a transverse vertical plane and in planes above the plane of said kerf cutter, said members each adapted to cooperate directly with flexible feeding means, and mechanism for effecting rotation of said members either separately or simultaneously at relatively low speed or at relatively high speed including for each member fast and slow predetermined speed transmission mechanism through which it, but not the other member, is driven, each transmission mechanism having a common terminal driving element for transmitting drive to its respective member at both speeds.

CERTIFICATE OF CORRECTION.

Patent No. 1,920,271.

August 1, 1933.

CHARLES F. OSGOOD.

It is hereby certified that error appears in the printed specification of the above numbered patent requiring correction as follows: Page 2, line 91, for "hauling" read haulage; page 3, line 51, for "880" read 80; and line 56, for "suitable" read suitably; page 4, line 138, claim 7, for "flexibly" read flexible; page 5, line 11, claim 9, for "side" read slide; and line 23, of same claim, after "operated" insert the word driving; and that the said Letters Patent should be read with these corrections therein that the same may conform to the record of the case in the Patent Office.

Signed and sealed this 30th day of October, A. D. 1934.

Leslie Frazer

(Seal)

Acting Commissioner of Patents.
